GRIPPER MECHANISM

William H. Wise and August A. Saul, Pittsburgh,
Pa., assignors to Miller Printing Machinery
Co., Pittsburgh, Pa., a corporation of Pennsyl-
vania

Application March 18, 1940, Serial No. 324,474

10 Claims. (Cl. 101—409)

This invention relates to gripper mechanism for use in connection with printing presses and the like. One of its objects is to improve the operation of grippers in printing presses and the like and reduce the noise incident to gripper operation. A further object of the invention is to provide improved means for urging the grippers into operative position when the grippers are in such position, but which may be rendered comparatively inoperative when the grippers move to inoperative position.

We provide gripper mechanism comprising a gripper, means for moving the gripper between operative and inoperative positions, shiftable means connected with the gripper and having movement consonant with the movement of the gripper and spring pressed means for urging the gripper into operative position when the gripper is in such position, said shiftable means and said spring pressed means being so constructed and arranged relatively to each other that movement of the shiftable means upon movement of the gripper to inoperative position renders the spring pressed means comparatively inoperative. The shiftable means may take the form of cam means cooperating with the spring pressed means, the cam means preferably being shaped so that movement thereof upon movement of the gripper to inoperative position renders the spring pressed means comparatively inoperative. The shiftable means may take the form of lever means connected with the gripper and the spring pressed means may have connection with a portion of the lever means so as to urge through the lever means the gripper into operative position when the gripper is in such position, and the spring pressed means may be disconnected from said portion of the lever means but may bear against another portion thereof when the gripper is in operative position. Such mechanism insures exceptionally accurate, reliable and quiet operation of the grippers at maximum efficiency and with the least waste of power.

Other details, objects and advantages of the invention will become apparent as the following description of a present preferred embodiment thereof proceeds.

In the accompanying drawings we have shown a present preferred embodiment of the invention, in which

Figure 1 is a fragmentary central vertical longitudinal cross-sectional view through the cylinder of a printing press showing a portion of one of the side frames and portions of the operating mechanism;

Figure 2 is a vertical transverse cross-sectional view through the cylinder showing a portion of the gripper operating and control mechanism;

5 Figure 3 is a fragmentary vertical transverse cross-sectional view through the cylinder taken on the line III—III of Figure 1 showing another portion of the gripper operating and control mechanism;

10 Figure 4 is a fragmentary enlarged vertical transverse cross-sectional view through a portion of the cylinder taken on the line IV—IV of Figure 1;

15 Figure 5 is a fragmentary enlarged vertical transverse cross-sectional view through a portion of the cylinder taken on the line V—V of Figure 1;

20 Figure 6 is a view similar to Figure 4 but showing the parts in a different operative position; and

25 Figure 7 is a view similar to Figure 5 but showing the parts in a different operative position.

Referring now more particularly to the drawings, the printing press illustrated is of the well known flatbed and cylinder type and comprises 30 opposed side frames one of which is shown fragmentarily in Figure 1 and designated by reference numeral 2, the opposite frame being of generally similar construction. Carried by each side frame is the usual bearing (not shown) for receiving one of the cylinder trunnions, as well known in the art. The press cylinder is designated by reference numeral 5 and has rigidly connected therewith at its opposite ends trunnions which are journaled in said bearings in 35 the side frames. The drive for the cylinder and bed may be conventional.

40 Mounted in the cylinder 5 adjacent the periphery thereof for limited rotary movement is a gripper shaft 12 having fixed thereto at intervals therealong a series of grippers 13. The function of the grippers 13 is to grip the sheets as they are registered to the press and hold the same in proper position on the cylinder during printing. In operation of the press the cylinder turns 45 in the direction of the arrow A (counterclockwise) in Figure 2. The press is provided with drop guides 14 (Figure 4) which are operated in conventional manner. As the means for operating the drop guides does not constitute the present invention such means is not shown in detail.

50 In operation of the press, as a sheet is advanced on the usual feed board (not shown) toward the cylinder 5 (the direction of sheet feed being generally from right to left at the top of the cylinder, viewing Figure 2) the drop guides are low-

ered into operative position to properly register the sheet. The front edge of the sheet strikes the drop guides so that the sheet is positioned to be seized by the grippers 13. After registering the sheet the drop guides are raised in usual manner. As the cylinder rotates the gripper shaft 12 is turned quickly in the clockwise direction viewing Figure 2 to seize the registered sheet at the proper instant and hold such sheet in place on the cylinder during printing. After the sheet has been printed the grippers are released by turning the gripper shaft 12 in the counterclockwise direction viewing Figure 4 to allow the sheet to be stripped from the cylinder by conventional strippers 16.

Journalized in the cylinder 5 is a shaft 17 whose axis is parallel to the axis of the cylinder and to which is fixed an arm 18 carrying at its extremity a gear segment 19 in mesh with a pinion 20 fixed to the gripper shaft 12. Also fixed to the shaft 17 outside the end of the cylinder is an arm 21 carrying at its outer end a cam follower 22 in the form of a rotatable sleeve. The cam follower 22 is adapted to ride in cam tracks 23 and 24 formed, respectively, by cams 25 and 26. The cams cause periodic turning of the shaft 17 during operation of the press, which turning results in swinging of the arm 18 and, through the segment 19 and the pinion 20, turning of the gripper shaft 12 to move the grippers 13 into and out of operative position.

The cam 25 is carried by the press frame 2 and is mounted therein for sliding movement toward and away from the cylinder 5 by pins 27 and 28 which are fixed to the cam 25 and which slide in bores in the frame 2. The cam 26 is carried by the press frame 2 and is mounted therein for sliding movement toward and away from the cylinder 5 by pins 29 and 30 which are fixed to the cam 26 and which slide in bores in the frame 2. Thus each of the cams 25 and 26 is movable into and out of cooperative relationship with respect to the cam follower 22 carried by the arm 21. The function of the cam 26 is to cause the grippers to move to operative position. The function of the cam 25 is to cause the grippers to move to inoperative position. The cam 26 also performs an additional function in that if the grippers should be in operative position when the follower 22 engages the cam 26 such cam will cause the grippers first to be moved to inoperative position and then to be returned to operative position. Similarly, the cam 25 also performs an additional function in that if the grippers should be in inoperative position when the follower 22 engages the cam 25 such cam will cause the grippers first to be moved to operative position and then to be returned to inoperative position. Means not shown are provided for moving the cams 25 and 26 axially of the pins 27, 28, 29 and 30 to insure against closing of the grippers when no sheet is registered to the drop guides. Such means are well known to those skilled in the art and constitute no part of the present invention.

Fixed to the gripper shaft 12 is a cam 31 having a generally radial portion 32. Adjoining the radial portion 32 of the cam at the outer extremity of such portion is a circular cam portion 33 which extends around the cam from the radial portion 32 through an angle of approximately 160°. The remainder of the cam surface has no function and for convenience is curved gradually inwardly from the extremity of the circular por-

tion 33 to the inner end of the radial portion 32 as shown in Figure 5.

Carried by the cylinder is a fixed pin 34 serving as a bearing for a link 35 one end of which is rotatably mounted upon said pin. Pivoted to the opposite end of the link 35 is a head 36 fixedly fastened to a rod 37 by a pin 38. At its opposite end the rod 37 is slidably received within a socket 39 having a bearing edge 40 bearing in a notch 41 in a bar 42 forming part of the cylinder 5. Surrounding the rod 37 and bearing against an annular projection 43 on the head 36 is a coil spring 44 the opposite end of which bears against a shoulder 45 on the socket 39. Thus the spring 44 in effect presses between a fixed portion of the cylinder and the head 36. The head 36 is pivoted to the link 35 by a pin 46, which pin also carries a roller 47 positioned to engage the cam 31.

When the grippers 13 are in inoperative or open position the roller 47 rides on the circular portion 33 of the cam 31, as shown in Figure 7. When the parts are in such position the reaction of the roller 47 on the cam is directed generally radially of the cam so that the spring 44 has no tendency to urge the gripper shaft 12 in either direction. There is a slight tendency to hold the gripper shaft in fixed position due to the friction between the roller 47 and the cam 31.

When the gripper shaft is turned to move the grippers into operative position the roller 47 rides from the circular portion 33 of the cam 31 to the radial portion 32 thereof, passing from the portion 33 to the portion 32 just as the grippers snap to operative or closed position. Figure 5 shows the position of the parts when the grippers are closed. In such position the force of the spring 44 is directed fully against the radial portion 32 of the cam 31, thus firmly pressing the grippers into closed position. As the gripper shaft is turned to open the grippers in a subsequent operation the roller 47 rides from the radial portion 32 of the cam onto the circular portion 33 when it becomes relatively inoperative to urge the gripper shaft in either direction of rotation.

Fixed to the gripper shaft 12 is a lug 48 forming a toggle member through which the gripper shaft may be urged toward either of its extreme positions after it passes center. Pivoted to the toggle lug 48 by a pin 49 is a head 50 fixed on a rod 51. At its opposite end the rod 51 is mounted on the cylinder 5 similarly to the mounting of the lower end of the rod 37 as shown in Figure 2. Surrounding the rod 51 and bearing against an annular projection 56 on the head 50 is a coil spring 57 the opposite end of which is backed by a portion of the cylinder. Thus the spring in effect bears between a portion of the cylinder and the head 50 which is pivoted to the toggle lug 48. As the gripper shaft 12 moves from one position to the other the toggle lug 49 passes center so that the toggle spring 57 is effective in either position of the gripper shaft for urging such shaft toward its extreme position. The toggle spring 57 is of less strength than the spring 44, the function of the toggle spring being simply to insure that the gripper shaft 12 completes its movement in each direction. The spring 44 supplies the force mainly relied upon to urge the grippers firmly into operative position to hold the sheets on the cylinder.

While we have shown and described a present preferred embodiment of the invention it is to be distinctly understood that the invention is not limited thereto but may be otherwise variously

embodied within the scope of the following claims.

We claim:

1. Gripper mechanism comprising a gripper, means for moving the gripper between operative and inoperative positions, cam means connected with the gripper and having movement consonant with the movement of the gripper and spring pressed means for urging the gripper into operative position when the gripper is in such position, said cam means and said spring pressed means being so constructed and arranged relatively to each other that movement of the cam means upon movement of the gripper to inoperative position renders the spring pressed means comparatively inoperative.

2. Gripper mechanism comprising a gripper, means for moving the gripper between operative and inoperative positions, cam means connected with the gripper and having movement consonant with the movement of the gripper and spring pressed means bearing against the cam means and through the cam means urging the gripper into operative position when the gripper is in such position, the cam means being shaped so that movement thereof upon movement of the gripper to inoperative position renders the spring pressed means comparatively inoperative.

3. Gripper mechanism comprising a gripper, means for moving the gripper between operative and inoperative positions, lever means connected with the gripper and having movement consonant with the movement of the gripper and spring pressed means having connection with a portion of the lever means so as to urge through the lever means the gripper into operative position when the gripper is in such position and disconnected from said portion of the lever means but bearing against another portion thereof when the gripper is in inoperative position.

4. Gripper mechanism comprising a gripper, means for moving the gripper between operative and inoperative positions, means having an abutment connected with the gripper and having movement consonant with the movement of the gripper and spring pressed means bearing against said abutment when the gripper is in operative position to urge through said second mentioned means the gripper into operative position, said second mentioned means moving upon movement of the gripper out of operative position so as to break contact between said spring pressed means and said abutment.

5. Gripper mechanism comprising a gripper, means for moving the gripper between operative and inoperative positions, cam means connected with the gripper and having movement consonant with the movement of the gripper, the cam means having an abutment portion, and spring pressed means bearing against said abutment portion and through the cam means urging the gripper into operative position when the gripper is in such position, the cam means moving upon movement of the gripper out of operative position so as to separate the spring pressed means from the abutment portion.

6. Gripper mechanism comprising a gripper, means for moving the gripper between operative and inoperative positions, cam means connected with the gripper and having movement consonant with the movement of the gripper, the cam

means having an abutment portion, and spring pressed means bearing at all times against the cam means and when the gripper is in operative position bearing against said abutment portion whereby through the cam means to urge the gripper into said position, the cam means acting upon movement of the gripper out of operative position to cam the spring pressed means away from said abutment portion.

10 7. Gripper mechanism comprising a gripper, means for moving the gripper between operative and inoperative positions, cam means connected with the gripper and having movement consonant with the movement of the gripper, the cam means having an abutment portion, a pivot, a link having one end carried by said pivot, a follower carried by said link and at all times urged against the cam means, the follower bearing against said abutment portion and through the cam means urging the gripper into operative position when the gripper is in such position, the cam means moving upon movement of the gripper out of operative position so as to separate the follower from the abutment portion.

15 8. Gripper mechanism comprising a gripper, means for moving the gripper between operative and inoperative positions, cam means connected with the gripper and having movement consonant with the movement of the gripper, the cam means having an abutment portion, a pivot, a link having one end carried by said pivot, a spring pressed rod pivoted to the other end of the link, said second mentioned end of the link having means bearing at all times against the cam means and when the gripper is in operative position bearing against said abutment portion whereby through the cam means to urge the gripper into said position, the cam means acting upon movement of the gripper out of operative position to cam said means on the second mentioned end of the link away from said abutment portion.

20 9. Gripper mechanism comprising a gripper, means for moving the gripper between operative and inoperative positions, cam means connected with the gripper and having movement consonant with the movement of the gripper, the cam means having an abutment portion, spring pressed means bearing at all times against the cam means and when the gripper is in operative position bearing against said abutment portion whereby through the cam means to urge the gripper into said position, said spring pressed means when the gripper is in inoperative position bearing against a portion of the cam means so as to have comparatively little, if any, effect upon the gripper.

25 10. Gripper mechanism comprising a gripper, means for moving the gripper between operative and inoperative positions, cam means connected with the gripper and having movement consonant with the movement of the gripper and spring pressed means engaging the cam means, the cam means being so constructed and arranged that as the gripper moves into operative position the spring pressed means will bear upon a portion thereof causing the gripper through the cam means to be pressed into operative position.
